UNITED STATES PATENT OFFICE.

DAVID L. NEWCOMB, OF SAN DIEGO, CALIFORNIA.

COUNTER.

No. 848,843.

Specification of Letters Patent.

Patented April 2, 1907.

Application filed March 3, 1903. Serial No. 145,931.

To all whom it may concern:

Be it known that I, DAVID L. NEWCOMB, a citizen of the United States, residing at San Diego, in the county of San Diego and State of California, have invented a new and useful Counter, of which the following is a specification.

My invention relates to a device which will mechanically indicate the number of times a certain operation is performed, and the device while particularly designed to be used in connection with voting-machines for registering the number of votes cast is adapted for many other uses.

15 A leading feature of my invention and one which differentiates the invention from all others is the employment of a strip or tape which is severable and which is actuated by the device and pushed out step by step in such a way that one end of the strip being free and unconfined the unconfined and exposed portion becomes longer step by step and is accessible so that the exposed part of the strip may be severed from the unexposed 25 part—for instance by tearing off when the count has been completed.

One object of my invention is to provide a counter which will be absolutely accurate in operation and proof against fraudulent operation.

30 Another object of my invention is to provide a mechanism of the character described which is exceedingly simple and which accomplishes the desired object with the fewest parts and dispenses as far as possible with small intricate parts.

The range or registering limit of the counter is independent of the number of working parts provided—that is, the range of many 40 counters is limited by the number of registering-wheels employed and if a high number is to be registered many wheels must be used—while in the present invention no more parts are required to indicate five thousand than 45 are required to indicate less than a dozen or even one or two.

Another object of my invention is to provide a new and improved actuating device which consists of only one piece and which 50 acts both as an operating part and a lock.

Briefly, my invention consists of a strip which contains definite marks or symbols and means for moving said strip step by step and bringing the symbols sequentially into a 55 definite position.

Referring to the drawings, Figure I is a perspective view of the complete device. Fig. II is a plan view, on a reduced scale, of the complete device. Fig. III is a section taken on line III III, Fig. II, showing the operating mechanism of the device, portions of the frame being shown in section. Fig. IV is a transverse sectional view taken through the spool, showing the means for attaching the strip or tape to the spool. Fig. V is a perspective of the spool. Fig. VI is a perspective of a stud which helps to guide the strip and also serves as a support for the tension-band. Fig. VII is a perspective of the tension-band. Fig. VIII is a detail perspective 70 of the operating-rod. Fig. IX is a perspective of the sprocket-drum and double ratchet. Fig. X is a perspective of the stripper. Fig. XI is a perspective of the guard detached and a portion of the tape or numeral-strip. Fig. XII is a perspective of the spring which holds the operating-rod in engagement with the double ratchet.

1 designates the frame of the device, which may preferably be of sheet metal, and comprises a front frame 2 and side wings 3 and 4.

5 designates a spool. The shaft or sleeve 6 of the spool is hollow and extends through and beyond one of the flanges.

7 is an arm, one end of which is pivotally 85 attached to the wing 3, as at 8, preferably by a rivet. The arm is not riveted so tightly but that it may be swung around on the rivet when it is desired to swing the arm away from the end of the spool. The arm 7 90 is formed, preferably, of spring metal, and its rear end is provided with a trunnion 9. The hollow shaft of the spool 5 is mounted on a stud 10, which projects from the wing 4, as shown in dotted line in Fig. II. The trunnion 9 fits in the end of the hollow shaft 6, thereby holding the arm 7 in position from swinging, and the spring-arm 7 frictionally bears against the spool and serves to hold the spool in position on the stud 10 and also acts 100 as a drag to prevent the spool from rotating except when the strip is being reeled off.

11 is a sprocket-drum provided with two opposite sets of teeth 12 and a hollow shaft 13. The shaft 13 projects beyond each end 105 of the drum, and at one end of the shaft is mounted a double ratchet, consisting of ratchets 14 and 15 placed face to face, the teeth of which are oppositely disposed. The hollow shaft of the sprocket-drum 11 is 110

mounted on a stationary pin 16, which pin is carried by the opposite wings 3 and 4.

17 is a stud which is rigidly mounted on the wing 4 and lies parallel with the shaft of the sprocket-drum and slightly to the rear of and below the sprocket-drum. The stud 17 is provided with a reduced neck 18, having a head 19 on its outer end.

20 is indicating means, comprising a strip 10 or tape which is wound upon the spool 5. The end of the strip is fastened to the spool 5, as shown in Fig. IV, by means of a spring-clip 21. The spring-clip 21 is segmental and covers more than one hundred and eighty degrees. The end of the strip is wound about the shaft of the spool, and the clip is sprung on the outside of the strip, nearly girdling the shaft, and it pinches the strip against the shaft 6 of the spool. The strip 20 is provided with definite symbols or numerals. The numerals are printed as close together as is consistent with allowing a sufficient space between each numeral to allow of the strip being torn between each numeral. The numerals are placed together as close as possible, so as to secure as many as possible with a given length of strip, and are arranged in a series increasing consecutively toward the free end of the strip one unit at a time. The strip is provided along each edge with rectangular perforations 22, spaced equally apart. (See Figs. II and XI.) Each perforation on one edge of the strip is exactly in line and registers with a corresponding perforation on the opposite edge of the strip. In other words, the strip is provided with numerous pairs of perforations, each pair being arranged on a transverse line passing midway between the adjacent numerals. The strip leads from the spool 5 down around the under side of the stud 17, then over around the sprocket-drum 11. The teeth 12 of the sprocket-drum 11 engage the perforations 22 of the strip 20. The strip leads over the stripper 23, (shown in Fig. III,) out through the front plate of the frame, and through the guard 24. The stripper 23 is a short curved plate (shown in detail in Fig. X) and is provided along its stripping edge 25 with two notches 26. The other edge of the stripper 23 is rigidly fastened to the front plate 2, while the stripping edge 25 of the stripper bears against the face of the sprocket-drum 11, the notches 26 allowing for the passage of the teeth 12. The function of the stripper 23 is to separate and guide the strip away from the sprocket-drum as the strip advances.

27 is a tension-band (shown in detail in Fig. VII) and is provided at its lower end with a loop 28, which is clasped around the neck 18 of the stud 17. The tension-band is provided with an upper curved portion 29, which lies over and closely against that part 65 of the strip which is in contact with the

sprocket-drum and frictionally bears upon the strip and holds the strip down upon the ratchet-drum 11. The guard 24 is provided with an aperture 30, as shown in Fig. XI, and at its lower edge is a thin plate 31, which forms a knife, against which the strip may be torn off. The aperture 30, if desired, may be filled with a transparent material, such as glass or mica, which will act as a protector for the strip. The advantage of employing a transparent protector is that by its use the numbers printed on the strip may not be erased and altered for fraudulent purposes.

32 is an operating-rod preferably provided at one end with a button 33. The other end 80 of the operating-rod is provided with a lug, which forms a retaining pawl or lock 34. The same end is also provided with a push pawl or detent 35. The detent 35 and lug 34 are staggered. The lug 34 lies over the 85 ratchet 15, while the detent 35 lies over the ratchet 14. The operating-rod 32 is slidably mounted in lugs 36 and 37, which are stamped and formed up from the frame 1. The lug 36 is provided with an elongated slot 90 38, which allows a slight amount of up-and-down movement of the operating-rod 32. Arranged on each side of the lug 37 are pins 39. The pins 39 form stops to limit the movement of the operating-rod 32. 95

40 is a leaf-spring having two members, the upper member being curved and provided with a lip 41. The lower member is straight and flat and is provided with a lug 42. The spring 40 lies along the upper edge 100 of the operating-rod 32 and lies through the elongated slot 38, and the lip 41 engages the upper wall of the elongated slot 38, while the lug 42 bears against the side of the operating-rod 32 and prevents the spring 40 from becoming dislodged. 105

43 is a retaining-pawl which is secured to the front wall 1 and bears against the ratchet 14 for preventing the reverse movement of the ratchet-drum at all times. 110

The operation of the counter is as follows: When the operating-rod is pushed in—that is, in the direction of the arrow as shown in Fig. III—the push-pawl 35 bears against a tooth of the ratchet 14, and thereby turns 115 the sprocket-drum 11 until the stop 39 strikes against the lug 37, which arrests the movement of the operating-rod, as the amount of movement which the operating-rod is allowed to have is just sufficient to 120 turn the sprocket-drum through a distance equal to the space between two teeth 12. Thus as the sprocket-drum is rotated it propels the strip a relative distance by reason of its teeth 12 lying in the perforations 22. 125 This action of the sprocket-drum unwinds the strip from the spool and shifts the strip by the stud 17 and around under the tension-band 27, the strip being pushed by the ratchet-drum over the stripper and out through the 130

guard 24 and a new symbol or number brought into place within the aperture 30. The retaining-pawl 43, bearing against the teeth of the ratchet 14, prevents the backward movement of the ratchet-drum, while the drum cannot be rotated forward farther by pulling on the strip for the reason that the lug 34 stands in front of a tooth of ratchet 15. When the operating-rod is retracted, the detent 35 must travel up over the top of the tooth immediately behind it. Therefore the operating-rod will be tilted slightly, and this tilting action is allowed by the elongated slot 38. The lug 34 is raised up over the tooth 15 as the operating-rod 42 is retracted by reason of the detent 35 sliding up the inclined face of the tooth 16. As soon as the operating-rod has been retracted sufficiently the spring 40 snaps the detent 35 back of the succeeding tooth. In Fig. III the operating-rod is shown as about in mid-stroke, the detent 35 having just snapped off and dropped behind the tooth 16. The lug 34 acts as a lock to prevent forward rotation of the ratchet-drum at any time other than when it is being regularly actuated by the operating-rod, while the retaining-pawl 43 also positively prevents rearward movement of the ratchet-drum at all times. The continued advance and retraction of the operating-rod causes the shifting of the strip step by step and bringing the numerals sequentially into position. The number of times that the operating-rod is actuated is indicated by the numeral on the strip.

When this device is used in connection with a voting-machine to indicate the number of votes cast, it is desirable that the strip be torn off at the knife 31 to prevent fraud. This tearing of the strip is facilitated by forming the perforations 22 between adjacent numerals, so that the strip will be weaker at those points. Therefore as the tears will occur at the points between numerals the numerals will not be mutilated by tearing the paper or other material forming the strip. When the counter is used in connection with a voting-machine for registering votes, it may be desirable to provide for the counter being operated a few times and advance the strip several steps without running any of the numerals into view.

It may be desirable to have on the strip immediately before the numerals a series of names which will be consecutively brought into view by the preliminary steps of the strip. These names may convey pertinent information to the election officials, showing that the device is in perfect working order, &c., as a preliminary of the actual count of the vote.

It is evident that various changes may be made in the herein-described embodiment without departing from the spirit of my invention.

What I claim, and desire to secure by Letters Patent of the United States, is—

1. In a counter, a strip, means for propelling said strip embracing a plurality of ratchets having oppositely-facing teeth, an operating-rod, a push-pawl formed rigidly on said rod and movable over one of said ratchets, and a lug on said rod movable into position for engagement with the other ratchet. 70

2. In a counter, a frame, a strip provided with definite symbols, means for supporting said strip in a compact form in said frame, a sprocket-drum mounted on the frame, said strip passing over said sprocket-drum, a stripper comprising a plate of spring metal, 75 the stripping edge of said plate being provided with two notches, said stripper being attached to said frame, the stripping edge of said stripper bearing against said sprocket-drum, said notches registering with the teeth of said 80 sprocket-drum and allowing rotation of the same. 85

3. In a counter, a frame formed of a single piece of sheet metal, a strip provided with a series of definite symbols, means for supporting said strip in a compact form in said frame, a drum rotatably mounted on said frame, means on said drum for engaging said strip and actuating the same, a ratchet axially connected with said drum, a pair of lugs 90 formed out from one side of said frame, each lug having a slot, the lug nearest the ratchet having an elongated slot, an operating-rod passing through both of said slots, means on the end of said operating-rod for engaging 95 said ratchet, a folded flat spring interposed between the upper wall of said elongated slot and the upper face of said operating-rod, a lip formed on the upper member of said spring hooked against the upper wall of the 100 slot, and a lug on the lower member of the spring bearing against the side of said operating-rod and holding said spring in position. 105

4. In a counter, a frame formed of a single piece of sheet metal, a strip provided with a series of definite symbols, means for supporting said strip in a compact form in said frame, a drum rotatably mounted on said frame, means on said drum for engaging said strip and actuating the same, a ratchet axially 110 connected with said drum, a pair of lugs formed from one side of said frame, each lug having slots, the lug nearest the ratchet having an elongated slot, an operating-rod passing through both of said slots, means on the 115 end of said operating-rod for engaging said ratchet, and a folded flat spring interposed between the upper wall of said elongated slot and the upper face of said operating-rod. 120

5. In a counter, a frame, a spool rotatably mounted at one end on said frame, a spring-arm pivoted to said frame and supporting the other end of the spool and frictionally bearing against said spool, a strip wound on said spool, said strip having a series of definite 125 130

symbols, and means for actuating said strip step by step and causing said symbols to sequentially appear at a definite point.

6. In a counter, a frame, a strip provided with a series of definite symbols, means for retaining said strip in a compact form in said frame, a drum rotatably mounted on said frame, means on said drum for engaging said strip and actuating the same, the front plate of said frame having an aperture, a guard covering said aperture, a stripper bearing against said drum, said strip passing over said drum and stripper and through the front plate of said frame and through said guard.

7. In a counter, a frame, a strip provided with a series of definite symbols, a guard on said frame, said guard having a sight-aperture, means on said frame for propelling said strip through said guard and projecting said symbols sequentially in said sight-aperture, and a plate having a thin edge forming the lower wall of said sight-aperture.

8. In a counter, a frame, a strip provided with a series of definite symbols, a guard on said frame, said guard having a sight-aperture, means on said frame for propelling said strip through said guard and projecting said symbols sequentially in said sight-aperture, and a knife carried by said guard.

9. In a counter, a frame, a strip provided with a series of definite symbols, a guard on said frame, said guard having a sight-aperture, and means on said frame for propelling said strip through said guard and projecting said symbols sequentially in said sight-aperture.

10. In a counter, a frame, a strip provided with a series of definite symbols, means for supporting said strip in a compact form on said frame, a drum rotatably mounted on said frame, means on said drum for engaging said strip, and propelling the same, a double ratchet axially connected with said drum, an operating-rod slidably mounted on said frame, a lug on the end of said operating-rod engaging the teeth of one of said ratchets, a detent formed near the end of said operating-rod and engaging the other ratchet, said detent and lug being spaced apart, and means for yieldingly holding the working end of said operating-rod close to said double ratchet.

11. In a counter, a frame, a strip provided with a series of definite symbols, means for supporting said strip in a compact form on said frame, a drum rotatably mounted on said frame, a double ratchet connected with said drum, the teeth of one of said ratchets facing opposite from the teeth of the other ratchet, an operating-rod slidably mounted on the frame, one end of the operating-rod being formed in a detent which engages one of said ratchets, a lug on said operating-rod engaging the teeth of the other ratchet, and

means on the drum for engaging said strip and propelling the same.

12. In a counter, a strip provided with a series of definite symbols, means for supporting said strip in a compact form in said frame, a drum rotatably mounted on the frame, a ratchet connected to said drum, means on the drum for engaging said strip and propelling the same, a ratchet connected with the drum, an operating-rod slidably mounted on the frame, one end of the operating-rod being formed as a detent and engaging said ratchet, and a spring retaining-pawl engaging said ratchet.

13. In a counter, a frame, a strip having a series of definite symbols, means for supporting said strip in a compact form in said frame, a drum rotatably mounted on said frame, means on said drum for engaging said strip, a ratchet connected to said drum, an operating-rod slidably mounted on the frame, one end of the operating-rod being formed as a detent and engaging said ratchet, means for yieldingly holding said detent in engagement with said ratchet, and means for normally locking said drum from movement in both directions.

14. In a counter, a frame, a strip provided with a series of definite symbols, means for supporting said strip in a compact form in said frame, a drum rotatably mounted on said frame, means on said drum for moving said strip, a ratchet connected with said drum, an operating-rod, means for supporting said operating-rod embracing a lug having an elongated slot, a pawl on the edge of said operating-rod, and a spring engaging said operating-rod and forcing said pawl against said ratchet, and means for positively locking the teeth of said operating-rod.

15. In a counter, a frame, a strip provided with a series of definite symbols, means for supporting said strip in a compact form in said frame, a drum rotatably mounted on said frame, means on said drum for moving said strip, a ratchet connected with said drum, an operating-rod, means for supporting said operating-rod embracing a lug having an elongated slot, a pawl on the end of said operating-rod, and a spring engaging said operating-rod and forcing said pawl against said ratchet.

16. In a counter, a frame, a strip provided with a series of definite symbols, means for supporting said strip in a compact form in said frame, means for actuating said strip, a drum in said frame, a ratchet connected with the drum, an operating-rod, means on the frame slidably supporting the operating-rod and allowing it an up-and-down movement, and a push-pawl on the end of said operating-rod for engaging said ratchet.

17. In a counter, a frame, a spool rotatably mounted on the frame, a strip wound on the spool, said strip being provided with a

series of perforations and with a series of symbols having a definite relation to the perforations, a sprocket-drum rotatably mounted on the frame, said strip passing over the 5 sprocket-drum, teeth on the drum engaging the perforations in said strip, a stud having a contracted neck, a tension-band having a loop at its lower end, said loop encircling said neck, the upper end of the tension-band being hooked over the strip and pressing the strip against the surface of the sprocket-drum, and means for rotating said sprocket-drum step by step and bringing the symbols on said strip sequentially into a definite position. 15

18. In a counter, a frame, two rotatable elements thereon, a strip coiled on one element but not on the other, the latter element having teeth, the strip having perforations 20 and symbols and making operative connection with the toothed element, a tension-band curved substantially concentric with the toothed element and holding the strip in contact with the element, and a rod provided 25 with a retaining-pawl and a push-pawl for rotating the said toothed element step by step and sequentially bringing said symbols into a definite position.

19. In a counter, a strip provided with a 30 series of perforations, a series of symbols placed in definite relation to the perforations, means for actuating said strip step by step, and bringing said symbols sequentially into a definite position, and means for locking said 35 strip.

20. In a counter, a frame, a spool having a shaft extending beyond one of the flanges thereof, a stud on the frame, said shaft being mounted on said stud, means for retarding 40 the rotation of said spool, a strip wound on said spool, said strip being provided with a series of perforations along the edge thereof and with a series of symbols arranged thereon in definite relation to the perforations, a 45 sprocket-drum mounted on the frame, teeth on the sprocket-drum, said strip passing over said drum, the teeth of the drum engaging the perforations in the strip, and means for rotating said drum step by step and bringing 50 the symbols on said strip sequentially into a definite position, said strip being severable and having a free unconfined end which is accessible, so that the exposed portion may be severed from the rest of the strip, and means for locking said strip. 55

21. In a counter, a frame, a spool rotatably mounted on the frame, means for frictionally retarding the rotation of the spool, a strip wound on the spool, said strip being 60 provided with a series of perforations along the edge thereof and having a series of symbols arranged thereon in definite relation to said perforations, a sprocket-drum rotatably mounted on the frame, teeth on the drum, 65 said strip passing over the drum, and the

teeth of said drum engaging the perforations in said strip, means for actuating said drum step by step and bringing the symbols sequentially into a definite position, said strip being severable and having a free unconfined end which is accessible, so that the exposed portion may be severed from the rest of the strip, and means for locking said strip. 70

22. In a counter, a frame, a spool rotatably mounted thereon, a strip wound thereon, 75 said strip being provided with a series of perforations along the edge thereof, a sprocket-drum rotatably mounted on the frame and provided with sprocket-teeth, said strip passing over said drum, the teeth of the drum engaging with the perforations in the strip, means for rotating said drum step by step and bringing said symbols sequentially into a definite position, said strip being severable and having a free unconfined end which is accessible, so that the exposed portion may be severed from the rest of the strip, and means for locking said strip. 80

23. In a counter, a strip provided with a series of perforations spaced equally apart 90 and arranged along each edge thereof, said strip being provided with definite symbols arranged between the two rows of perforations, each symbol occupying a position linearly midway of adjacent pairs of transversely-opposite perforations, means coacting with said perforations for actuating said strip step by step and bringing said symbols sequentially into a definite position, said strip being severable and having a free unconfined 95 end which is accessible so that the exposed portion may be severed from the rest of the strip, and means for locking said strip. 100

24. In a counter, a strip provided with rectangular perforations along each edge thereof, each perforation on one edge registering with a corresponding perforation on the opposite edge, said strip having definite symbols arranged between said perforations, each symbol bearing a definite relation to each 105 pair of opposite perforations, means coacting with said perforations for actuating said strip step by step and bringing said symbols sequentially into a definite position, said strip being severable and having a free unconfined end which is accessible so that the exposed portion may be severed from the rest of the strip, and means for locking said strip. 110

25. In a counter, a strip provided with 115 perforations, said perforations being spaced equally apart, said strip being provided with symbols spaced equally apart and arranged between the perforations, means coacting with the perforations for actuating said strip step by step and bringing said symbols sequentially into a definite position, said strip being severable and having a free unconfined end which is accessible so that the exposed portion may be severed from the 125 130

rest of the strip, and means for locking said strip.

26. In a counter, a strip provided with perforations along both sides thereof, said strip having definite symbols arranged between said perforations, means coacting with the perforations for actuating said strip step by step and bringing said symbols sequentially into a definite position, said strip being severable and having a free unconfined end which is accessible so that the exposed portion may be severed from the rest of the strip, and means for locking said strip.

27. In a counter, a flexible strip provided with a series of definite symbols and a series of perforations in definite relation to the symbols, means coacting with the perforations for moving said strip step by step and bringing the symbols sequentially into a definite position, said strip being severable and having a free unconfined end which is accessible so that the exposed portion may be severed from the rest of the strip, and means for locking said strip.

28. In a counter, a strip having definite symbols thereon, means for moving said strip step by step and bringing said symbols sequentially into a definite position, said strip being severable and having a free unconfined end which is accessible so that the exposed portion may be severed from the rest of the strip, and means for locking said strip.

29. A counter comprising a free-ended strip having symbols and perforations correspondingly spaced therealong; a sprocket fitting the perforations to advance the strip; a guard through which the free end of the strip extends, and a lock-ratchet for advancing the strip step by step through the guard.

30. A frame, a free-ended strip weakened at regular intervals and having symbols on the intervening portions, and means for positively moving said strip step by step a distance equal to the distance between adjacent weakened points and pushing the free end through said frame and means for locking said strip.

31. A frame, a free-ended strip, means for positively moving said strip step by step out of said frame, and means for positively locking said strip.

32. In a counter, a frame, a drum provided with indicating means, a double ratchet rotatable with said drum, an operating-rod slidably mounted on said frame, a lug on the end of said operating-rod engaging the teeth of one of said ratchets, a detent formed near the end of said operating-rod and engaging the other ratchet, said detent and lug being spaced apart, and means for yieldingly holding the working end of said operating-rod close to said double ratchet.

33. In a counter, a frame, a drum rotatably mounted on said frame and provided with indicating means, a double ratchet connected with said drum, the teeth of one of said ratchets facing opposite from the teeth of the other ratchet, and an operating-rod slidably mounted on the frame, one end of the operating-rod being formed in a detent which engages one of said ratchets, a lug being provided on said operating-rod engaging the teeth of the other ratchet.

34. In a counter, a frame, a drum provided with indicating means and toothed operating means, and a reciprocatory operating-rod provided with a detent for operating said toothed operating means and a lug for preventing accidental displacement thereof.

35. In a counter, a frame, a drum provided with indicating means, a double ratchet rotating with said drum, and a tilting, reciprocatory rod adapted to engage one set of ratchet-teeth to rotate the drum, said rod having a detent normally engaging the other set of ratchet-teeth.

In testimony whereof I have signed my name to this specification, in the presence of two subscribing witnesses, at Los Angeles, in the county of Los Angeles and State of California, this 6th day of January, 1903.

DAVID L. NEWCOMB.
